UNITED STATES PATENT OFFICE.

JOHN VOLLMER, OF BOSTON, MASSACHUSETTS.

ACID-STORAGE TANK.

SPECIFICATION forming part of Letters Patent No. 684,655, dated October 15, 1901.

Application filed April 24, 1901. Serial No. 57,195. (No model.)

To all whom it may concern:

Be it known that I, JOHN VOLLMER, a citizen of the United States, residing at Boston, in the county of Suffolk and State of Massachusetts, have invented a new and useful Improvement in Acid Receiving or Storage Tanks, of which the following is a full, clear, and exact description, reference being had to the accompanying drawings, forming a part 10 of this specification, in explaining its nature.

The invention relates to the herein-described improvement in acid receiving or storage tanks. Tanks of this character are largely used in the sulfite process of making 15 pulp for holding acid and for receiving gas from the digester. Heretofore such gas has been introduced into the tank by means of a brass or copper pipe permanently secured to the top of the tank, extending through it, and 20 also extending downward to within about eighteen inches of the bottom of the tank, the purpose of the pipe being to convey the gas and liquor from the digester to the acid-tank and also to deliver it in the acid-tank near 25 the bottom thereof, as such delivery is necessary for the proper combining of the gas with the acid, thereby making the acid more uniform in strength. This construction, however, is not found to be satisfactory in use on 30 account of the fact that the acid in which the pipe extends eats it to such an extent as to sever or perforate it and weaken it and form discharge-holes for the gas in all parts of the chamber, so that its use as a means for introducing the gas to the acid near the bottom 35 of the chamber is not to be depended upon. When the pipe has become thus perforated and damaged, it is necessary to remove it and substitute another, and this has always been 40 a matter of trouble and expense, in that it is necessary to remove all the acid from the tank before the pipe can be reached. It should be understood that these tanks are from ten to twenty feet high and that the pipes are from 45 two inches to six inches in diameter, that they are suspended from the top of the tank, and that therefore they are not readily accessible even after the acid has been drawn off. Pipes of lead are not readily attacked by the acid, 50 but they have not been used because of their weight and because of the vibration of the pipe, which very shortly breaks or severs it

near the head of the tank. Iron pipe cannot be used, because it will not stand the attacks of the acid.

My invention consists in the use of lead pipe which is reinforced and made stable by one or more stays of a metal of greater tensile strength, which is attached to the part of the pipe in the tank and is entirely covered 55 with lead within the tank, so that the acid 60 may not affect it. By the use of this means it becomes possible to employ lead pipe and to suspend it from the head of the tank without danger of its becoming detached therefrom because of its movement or oscillation.

The invention relates to features of construction which will be described in connection with the drawings, wherein—

Figure 1 is a view in vertical cross-section 70 of an acid receiving or storage tank and the feed-pipe. Fig. 2 represents a horizontal cross-section of the feed-pipe as reinforced. Fig. 3 is a modified form of the same.

Referring to the drawings, A represents an 75 acid receiving or storage tank of conventional form. It is generally lined with lead. It has the manhole a, by which its interior is reached. It has through its upper end or head B a hole b, through which the gas-feed pipe C is introduced into the chamber a' of the tank. This 80 feed-pipe has an open lower end c near the bottom of the tank, by means of which the gas is fed to the contents of the tank. It is made of lead and a metal of greater tensile 85 strength than lead. In the drawings I have represented it as combined with two longitudinal bars c' c'', of iron or steel, extending on the outside of the pipe, lengthwise of it, and upon 90 opposite sides of the pipe and each united to the pipe by a covering c'', of lead, brazed or otherwise attached to the pipe. These iron or steel bars may be provided with perforations c'', through which the lead may knit between the pipe and the outer covering. The 95 portions of the steel or iron bars inside the tank are entirely covered by lead, so that no portion of them can be reached by the acid. They extend downward as far as may be necessary for the proper support and suspension 100 of the pipe. They extend upward through the hole b in the head and have their upper ends c'' turned outward above the head to furnish ears or flanges to rest on supports c''.

beneath them, and thus act as the proper means for hanging or suspending the pipe in the chamber of the tank. I have described them as made of iron or steel; but they may be made of any other metal of suitable tensile strength. One bar only may be used or more than one.

In Fig. 3 as a modification I have represented the lead pipe as inclosed within an iron pipe, preferably perforated, which iron pipe and perforations are covered and filled with lead attached to the inner pipe and so that the iron pipe is entirely protected from the acid. The lead pipe has attached to it a wide lead flange D, which extends upon the head of the tank on its upper surface about the edge of the hole and is fastened to the head by screws or in any other desired way, and a gasket of acid-proof packing may be placed between the flange and the head, if desired. A lead pipe reinforced by protected means of the character specified has long life, because the lead resists the action of the acid and because the lead pipe, being stayed and supported, will not be moved by the gas to the extent that it would be moved if unsupported, and any movement that it may have is borne by the reinforcements rather than by the lead pipe itself.

Having thus fully described my invention, I claim and desire to secure by Letters Patent of the United States—

1. The improvement in acid receiving or storage tanks herein described, the same comprising a feeding-pipe of lead extending to near the bottom of the tank and there opening into the tank, a metallic reinforcement of greater tensile strength than lead combined with the outside of the pipe attached to the tank, to sustain the pipe and having that portion within the tank protected from acid by a covering of lead.

2. The combination of a tank for receiving or storing acid with a feed-pipe of lead, ex-

tending through the tank to near the bottom thereof where it opens, having one or more metal reinforcements of greater tensile strength and rigidity than lead combined with it in the tank to stiffen it, attached to the outside of the tank to support it, having the portion within the tank coated or covered with lead, which is also attached to the lead pipe.

3. The combination of an acid receiving or storage tank, a lead supply-pipe extending from without the tank through an end thereof to near the bottom of the tank, a metal reinforcement combined with the lead pipe to stiffen and sustain it in the tank and to also suspend it from the end of the tank, the metal reinforcement and lead pipe within the tank being united by a lead covering, which covers and protects the reinforcement from acid, and a lead flange extending from the lead pipe upon the end of the tank about the hole through which the pipe enters it.

4. The feeding-pipe for an acid receiving or storage tank, comprising a lead pipe, a metal reinforcement, having at its outer end means for attachment to the outside of the tank, and the said lead pipe having a lead flange which surrounds the pipe and the metal reinforcement.

5. The combination of a tank for receiving or storing acid and a lead supply-pipe having a metal reinforcement upon each side thereof of greater tensile strength and rigidity than the lead pipe united to the lead pipe by a covering of lead which protects it from the acid, the said reinforcements being opposed to each other and the ends of which outside the tank extend outward to act as supports by means of which the lead pipe and its reinforcements are suspended in the tank.

JOHN VOLLMER.
